(57) **CLAIM**

The ornamental design for a portion of a table top, as shown and described.

DESCRIPTION

FIG. 1 is an upper perspective view of a portion of a table top in accordance with a preferred embodiment of the present invention;

FIG. 2 is a lower perspective view of the table top shown in FIG. 1; and,

FIG. 3 is a top view of the table top shown in FIG. 1. The broken lines shown in the figures are for illustrative purposes only and form no part of the claimed design.
